CHAIR

Orval R. Platter, North Vernon, Ind., assignor to
 North Vernon Industries, Inc., North Vernon,
 Ind., a corporation of Indiana

Application February 17, 1934, Serial No. 711,745

6 Claims. (Cl. 155—117)

This invention relates to chairs, particularly to self adjusting chairs of the type commonly used on steamers, beaches, lawns, etc. and the object of the invention is to provide a chair of such design and construction that it affords a thoroughly dependable and comfortable seat in that the back of the occupant does not come in contact with the lower portion of the back of the chair which prevents contact with the rod to which the seat and back are fixed and to further provide a chair which is not only adjustable to various reclining positions but is capable of being folded into a very compact condition when not in use or for transportation.

Referring to the accompanying drawings, which are made a part hereof and on which similar reference characters indicate similar parts,

Figure 1 is a perspective view of the chair with a foot rest and canopy attached thereto.

Figure 2 is a side elevation of the chair, the dotted lines indicating the extreme forward position of the back and seat,

Figure 3 is a section on line 3—3 of Figure 2, and

Figure 4 is a side elevation of a modified form of the chair.

In the drawings reference character 10 indicates the front legs of the chair positioned parallel to each other and connected by parallel rods 11 and 12 near the bottom and mid points, respectively. The rods are rigidly fixed in any suitable manner to the legs 10. The rear legs 13 are pivoted to the upper ends of the legs 10 by bolts or pins 14 and extend rearwardly and downwardly being connected by a rod 15 fixed to each adjacent their lower ends. Arm rests 16 pivotally connected on the pins 14 at their front ends extend rearwardly and are pivotally connected by bolts or pins 17 at their rear ends to the downwardly extending brace members 18.

Diagonal brace members 19 are pivotally connected at their upper ends on the rod 12 with the upper portion thereof projecting beyond the front legs 10. The members 19 extend rearwardly and downwardly where they are pivotally connected to the lower ends of brace members 18 by a rod 20. The rod 20 is adapted to seat in the notches 21 formed in the upper edge of the rear legs to hold the frame work in position, as shown in Figure 2. The brace members 19 are positioned adjacent the inner surface of the legs and the brace members 18 are adjacent the inner surfaces of the brace members 19. The arm rests are positioned against the outside surfaces of the rear legs and the brace members 18. This arrangement permits the framework to be folded when the rod 20 is lifted out of the notches 21.

The back is formed of side members 22 pivoted near their centers on the pins 17 adjacent the inner surfaces of the brace members 18 and

are connected at their upper ends by a rod 23 rigidly fixed thereto.

The seat is formed of side rails 24 connected at their ends by parallel rods 25 with the front ends of the side rails resting on the upper ends of the brace members 19. The lower ends of the side members 22 of the back in the construction shown in Figure 2 are pivotally connected to the side rails by bolts or pins 26 at a point spaced from the extreme rear ends of the side rails 24 for a purpose which will be later described. In the modified form shown in Figure 4 the lower ends of the side members 22 are pivotally mounted on the rear seat rod 25 instead of at the points shown in Figure 2.

The seat is provided with a bottom form of several layers of suitable flexible material, preferably canvas, one layer 27 is stretched and secured to the side rails and the other layer 28 is stretched and secured to the rods 25. Strips 29 of suitable material are fixed to the underside of the side rails on the material forming the seat bottom to prevent undue wear at this point due to sliding of the side rails on the upper ends of the brace members 19. The strips 29 project outwardly 25 along the side rails to prevent contact of the seat material with the inner surfaces of the legs 10 as shown in Figure 3, to eliminate undue wear along this surface.

The back is provided with a strip 30 of suitable material secured at one end to the rod 23 and secured at the other end to the rear rod 25 of the seat. The strip 30 at its lower end extends around the back of and under the rod 25 with the strip 28 of the seat extending over the top 35 of this rod as shown in Figure 2 or where desired, the strip 30 can be positioned around the front of the rod with the seat strip 28 extending under the rod and around the back thereof, as in Figure 4.

In order to further safe-guard the back of the occupant of the chair, straps 31 and 41, of material similar to that used on the back and seat, are stretched between and secured to the side members 22 of the back. These straps serve to support the back in the region of the kidneys and are termed "kidney straps".

The glide of the seat is limited by means of loop members 32 fixed in any suitable manner on the inner surfaces of the side rails around the rod 12, as shown in Figure 2.

In order to protect the occupant from sun and rain, a canopy 33 formed on a suitable framework and covered by the same material as used for the seat and back is provided and detachably connected by wing nuts and bolts 34 or any other suitable securing means to the upper ends of the side members 22 of the back of the chair.

A foot and leg rest formed of side members 35 and cross members 36 connected by a series of 60

slats 37 is provided and is supported by the legs 38 pivotally connected at the outer ends of the sides 35. The legs are connected by a rod 39. The inner ends of the sides 35 are provided with hooks 40 which engage over the front rod 25 of the seat portion. Both the canopy and foot and leg rest are readily detachable and may be used when desired, the complete chair being clearly shown in Figure 1.

10 It may be readily seen that the rod to which the cloths of the seat and back are attached is set back of the pivotal point or the pins 26 which connect the side members of the back and the side rails of the seat and the straps across the back 15 cooperate with the positioning of pins 26 to prevent the back or spine of the occupant from coming in contact with this rod, thus providing a comfortable seat and back.

20 In the construction shown in Figure 4, the straps 31 and 41 not only provide additional support for the occupant's back but assist in preventing the back from coming in direct contact with this rod.

With the back pivoted at the point indicated by bolts or pins 17 a smooth easy gliding back and seat is provided and which is self-adjusting by merely shifting of the occupant's body. The pressure of the front ends of the side rails on the upper ends of the brace members 18 hold the seat in any one of a number of positions, the extent of the movement is controlled by the loop members 32. The dotted line position shows the extreme reclining position.

35 The chair may be quickly folded into a fairly compact bundle for transportation or storage by simply lifting the rod 20 out of the notches 21 and forcing the brace members together. The particular construction described above, due to the arrangement of the various parts, takes up a 40 comparatively small floor space when set up or when in folded condition.

Having thus fully described my said invention, what I claim as new and desire to secure by Letters Patent, is:

45 1. A chair of the kind described comprising a supporting framework, a seat portion provided with a flexible bottom connected between front and rear cross rods and slidably mounted in said framework, a back portion pivoted intermediate 50 its ends in said framework with the lower ends pivoted intermediate the ends of said seat portion to support same, a flexible back connected taut between the top of said back portion and the rear cross rod of said seat portion, and a flexible strap connected taut across the lower 55 end of said back portion beneath said flexible back to assist in supporting a person's back in such a manner as to be spaced forwardly from the rear edge of said seat portion.

60 2. A chair of the kind described comprising a pair of front legs, a pair of rear legs connected to the tops of said front legs, pairs of braces supported on said rear legs, one pair of which are pivotally connected to said front legs, arm rests connecting the tops of said front legs and other pair of said braces, cross connecting members between the legs spacing them apart for a seat, a framework defining a seat portion provided with a flexible bottom connected to front and rear cross rods with the front edge thereof slidably positioned between said front legs, a second framework defining a back portion pivotally intermediate its ends at the intersection of said arm rests and last-mentioned braces with its lower ends pivotally

connected and spaced from the rear cross rod of said seat portion to support same, a flexible back connected taut between the top of said back portion and the rear cross rod of said seat portion and a flexible member connected taut to sides of and across said back portion and to the rear of said flexible back, so that a person occupying said chair does not contact the rear cross rod of said seat portion.

3. A chair of the kind described comprising 10
parallel front legs, parallel rear legs connected to
the tops of said front legs extending rearwardly
and downwardly, diagonally positioned brace
members detachably positioned on the rear legs
extending upwardly, one pair of which is pivot- 15
ally connected to the front legs, arm rests connect-
ing the upper ends of said front legs and the
upper ends of the other pair of said brace mem-
bers, side rails connected by rods defining a seat
framework, a flexible member fixed between said 20
rods, side members connected by a rod at their
upper ends defining a back framework, said side
members being pivoted intermediate their ends
at the intersection of said last-mentioned brace
members and said arm rests, with their lower ends 25
pivotally connected intermediate the ends of said
seat, a flexible back member fixed taut between
said rod of the back and the rear rod of the seat
and a flexible member connected taut across the
lower end of said side members of the back and to 30
the rear of the flexible back member.

4. A folding chair comprising connected leg frames, one at each side of the chair, each leg frame having a front and rear leg pivotally connected at their upper ends, an arm rest pivotally connected with the legs in each frame, a prop pivoted to the arm and releasably supported on the rear leg, bracing means between the front and rear leg, a back pivotally connected to each arm, a seat pivoted at the rear to the lower end of the back, means shiftably supporting the front of the seat on the leg frames.

5. A folding chair comprising connected leg frames, one at each side of the chair, each leg frame having a front and a rear leg connected together near their upper ends, an arm rest pivotally connected to each leg frame, a back pivotally connected to said arm rests, a seat pivoted at the rear to the back adjacent to its lower end, means supporting the seat for backward and forward movement with respect to the leg frames, bracing means for the legs of each leg frame to maintain the spaced relation of the front to the rear legs and movable props arranged between the back of the chair and the rear legs. 55

6. A chair comprising connected leg frames, one at each side of the chair, each leg frame having foldable front and rear legs pivotally connected at the front of the chair, an arm rest pivotally connected to each leg frame adjacent to the top thereof, a back pivotally connected to said arm rests at the rear thereof, a seat pivoted at the rear to the back, means movably supporting the front of the seat in a manner to provide for adjustment of the seat and back of the chair to different positions in use, a movable prop between the back and one leg frame when the chair is set up, and means for bracing the legs when the chair is set up, said pivotal connections and proportioning of the parts permitting the legs, back and seat to be compactly folded upon movement of said prop from its back-supporting position.

ORVAL R. PLATTER.
